Attorney

UNITED STATES PATENT OFFICE.

LEWIS E. KELLY, OF OAKLAND, CALIFORNIA, ASSIGNOR TO HERBERT E. BOVENIZER
AND H. LUCILLE BOVENIZER, BOTH OF OAKLAND, CALIFORNIA.

PROCESS OF MAKING WATER-COLOR PRINTS.

Application filed February 11, 1922. Serial No. 535,751.

To all whom it may concern:

Be it known that I, LEWIS E. KELLY, a citizen of the United States, residing at Oakland, in the county of Alameda and State 5 of California, have invented certain new and useful Improvements in Processes of Making Water-Color Prints, of which the following is a specification.

My invention is a multi-water-color printing process and consists in the novel features 10 hereinafter disclosed.

Referring to the annexed drawing in which my invention is illustrated and which forms a part of this specification:

15 Figure 1 is a face view of the zinc plate taken from the photograph of the original picture or design to be printed.

Figure 2 is a plan view of the complete wax impression taken from the zinc plate 20 shown in Figure 1 and the frame including said impression.

Figure 3 is a cross section of Figure 2 taken on line 3—3.

Figure 4 is a face view of a plaster of 25 Paris impression of a part of the wax impression shown in Figure 2, for printing said part a certain color such as red.

Figure 5 is a face view of a rubber impression of the plaster of Paris impression 30 shown in Figure 4.

Figure 6 is a face view of another plaster of Paris impression of another part of the wax impression shown in Figure 2 for printing said part another color such as gold.

35 Figure 7 is a face view of a rubber impression of the plaster of Paris impression shown in Figure 6.

Figure 8 is a view of a print in two water colors printed by my process, the parallel 40 hatching in different directions indicating two different colors, it being understood that the flame of the candle is formed by a plate similar to those shown in Fig. 5 and Fig. 7.

45 A zinc impression 1 is first taken of the original photograph to be printed and secured on a block 2, as shown in Figure 1.

A wax impression 3 is taken of the zinc impression 1 and secured on a block 4 within a frame 5 which surrounds and is secured to 50 said block. A plaster of Paris impression 6 is taken of a part of the wax impression 3. A rubber impression 7 is taken of the plaster of Paris impression 6. A plaster of Paris impression 8 is taken of the remaining part 55 of the wax impression 3. A rubber impression 9 is taken of the plaster of Paris impression 8.

The rubber impressions 7 and 9 which accordingly are intaglio are placed in the 60 printing press. A water color such as red is placed on the impression 7 and another water color such as gold is placed on the impression 9, surplus color being scraped from the surfaces of the impressions in the usual 65 manner. These inked impressions print the picture in the two water colors. A third plate in another color is, of course, used to produce the flame in the design illustrated.

The water color used as ink on the im- 70 pressions may consist of pigment, glycerine, water and any mucilaginous substance, such as gum arabic.

Having described my invention, I claim:

1. The process of making plates for mul- 75 ti-color printing which consists in first tak- ing a zinc plate of the picture to be printed, taking a wax impression from said zinc plate, taking different plaster of Paris im- 80 pressions of different parts of said wax im- pression and, taking rubber impressions of said plaster of Paris impressions, respec- tively.

2. The process of making an intaglio 85 printed plate, which consists in first taking a zinc plate of the picture to be printed, taking a wax impression from said zinc plate, taking a plaster of Paris impression of said wax impression, and taking a rubber impression of said plaster of Paris impres- 90 sion.

In testimony whereof I affix my signature.

LEWIS E. KELLY.
